UNITED STATES PATENT OFFICE.

PETER J. ACKERMAN, OF PATERSON, NEW JERSEY.

IMPROVEMENT IN COOKING-RANGES.

Specification forming part of Letters Patent No. 154,206, dated August 18, 1874; application filed May 9, 1874.

To all whom it may concern:

Be it known that I, PETER J. ACKERMAN, of Paterson, in the county of Passaic and State of New Jersey, have invented a new and useful Improvement in Cooking-Ranges, of which the following is a specification:

The invention will first be fully described, and then pointed out in the claim.

Figure 1 is a front elevation. Fig. 2 is a plan view. Fig. 3 is a horizontal section, and Fig. 4 a transverse sectional elevation.

A represents the fire-pot, B the oven, and C the warming-chamber, which are constructed with reference to building into a fire-place. Partitions D divide the oven and the warming-chamber each into two chambers, while E are doors at the front. H are flues at the outer ends of the oven, between which and flue I are dampers F F, while between flue J and the flue I that separates oven B and warmer C is the damper G.

By this construction the products of combustion may be made to pass over as well as under the oven, and then into exit-flue J, or, by closing the damper G and opening the dampers F F, they may be made to pass around the ends through flues H H, thence over the top of oven, and into exit-flue J. Thus the heat may be distributed wherever wanted about the oven, and very quickly.

Having thus described my invention, what I claim is—

The described combination, with fire-pot A, oven B, warmer C, escape-flue J, and flues leading over and under the oven, of the side flues H H and dampers F F G, as and for the purpose specified.

PETER J. ACKERMAN.
